CLAIM

We claim the ornamental design for a compact personal air purifier, substantially as shown and described.

DESCRIPTION

FIG. 1 is a perspective view of an air purifying device;
FIG. 2 is a front elevation view of an air purifying device;
FIG. 3 is a back elevation view of an air purifying device;
FIG. 4 is a top plan view of an air purifying device;
FIG. 5 is a bottom plan view of an air purifying device;
FIG. 6 is a side elevation view of an air purifying device;
and,
FIG. 7 is an opposite side elevation view of an air purifying device.
